CLAIM

The ornamental design for a water-repellent joist flashing, as shown and described.

DESCRIPTION

FIG. 1 is a front elevational view of the water-repellent joist flashing showing my new design;

In FIG. 2, the dotted line showing of a joist is for illustrative purposes only and forms no part of the claimed design.

FIG. 2 is a rear elevational view thereof;

In FIGS. 3 through 7, the jagged line showing denotes indeterminate length.

FIG. 3 is a right side elevational view thereof;

FIG. 4 is a left side elevational view thereof;

FIG. 5 is a top plan view thereof;

FIG. 6 is a bottom plan view thereof; and,

FIG. 7 is an isometric view thereof.
